UNITED STATES PATENT OFFICE.

JACOB S. JAMMER, OF NEW YORK, N. Y., ASSIGNOR TO WESTERN ELECTRIC COMPANY,
INCORPORATED, OF NEW YORK, N. Y., A CORPORATION OF NEW YORK.

MEANS FOR CONTROLLING ELECTRICAL TRANSMISSION.

Application filed June 17, 1922. Serial No. 568,940.

To all whom it may concern:

Be it known that I, JACOB S. JAMMER, a citizen of the United States, residing at New York, in the county of New York, State of New York, have invented certain new and useful Improvements in Means for Controlling Electrical Transmission, of which the following is a full, clear, concise, and exact description.

10 The invention relates to means for controlling the transmission gain or loss in a line transmitting currents of different frequencies, for instance a telephone line transmitting different frequencies in the voice frequency range, or a carrier line transmitting frequencies, for example, as high as 30,000 cycles per second and as low as 6,000 cycles.

It is customary, in long lines of such character, to insert repeaters giving transmission gains tending to counteract the attenuating effect of the line upon the currents transmitted. Ordinarily a potentiometer is associated with the repeater, in order that 25 when the line attenuation increases or decreases the potentiometer setting may be correspondingly adjusted to cause the repeater gain to be increased or decreased by an amount approximately the line attenuation 30 change as nearly as possible. However, the usual changes of line attenuation are greater for the currents of the higher frequencies being transmitted over the line than for the currents of the lower frequencies passing 35 over the line. This is true both as regards cases where currents of the voice frequency range are being transmitted and as regards cases where currents of higher frequencies, for instance 6,000 cycles and 30,000 cycles 40 are being transmitted. In the former cases the predominating influence in causing change of line attenuation usually is change in the temperature of the line; and in the latter cases the predominating influence generally is change of specific inductive capacity of the medium surrounding the line, due to change of dampness. Since the changes of line attenuation vary with frequency, it is clear that merely shifting the

potentiometer setting cannot entirely compensate for these changes, inasmuch as changes in the setting of the usual type of simple potentiometer cause repeater gain changes which are equal at all frequencies. The most complete compensation can only 55 be obtained by means for producing transmission gains or losses varying with frequency.

The present invention provides an attenuating device adjustable to give changes in 60 its transmission gain or loss which vary with frequency, and further, to provide such a device wherein movement of a single element may cause the adjustment necessary to effect the varying changes of gain or loss.

Another object is to provide a repeater comprising such a device, the device embodying resistance, inductance and capacity so proportioned and arranged that adjustment of the device may be made to so change 70 the gain of the repeater by different amounts for different frequencies as to compensate for changes in attenuation, due to weather changes for instance, in the line in which the repeater is connected. 75

Another object is to provide an attenuating device of the type referred to in the form of a voltage changing potentiometer possessing inherent transmission equalizing properties. 80

In the embodiment disclosed, the potentiometer device comprises a resistance and an anti-resonant loop for serial connection between the input leads to the device, and means for varying the amount of the series resistance in circuit and, in effect, simultaneously adjusting the output leads from the device to connect them across the loop and the proper proportion of the series resistance in circuit to cause the device to discriminate to the desired degree against the transmission of 85 relatively high frequencies from the input leads to the output leads in favor of the transmission of relatively lower frequencies from the input side to the output side of 90 the device. As is explained hereinafter, the purpose of this frequency discrimination is 95 to cause a distortion of the transmitted cur-

rents complementary to that due to the unequal line attenuation of the different frequencies, in order to neutralize the distortion due to such inequality of line attenuation.

Fig. 1 shows a repeater circuit embodying one form of the invention.

Fig. 2 shows a repeater circuit embodying another form of the invention.

10 Fig. 3 is a diagram for facilitating explanation of the design and operation of the system of Fig. 2.

In Fig. 1 a two stage push-pull electron discharge repeater is shown for repeating from a line section 3 which extends west to a line section 5, which extends east. The first stage of the repeater feeds the second stage through a gain adjusting potentiometer 10 consisting of resistances 11 and 12 and adjustable contacts 13 and 14 which may be so connected mechanically by suitable means (not shown) as to move toward or from each other simultaneously. A transmission equalizing shunt is provided, consisting of inductance 20, capacity 21, resistances 22 and 23, and adjustable contacts 24 and 25, electrically and mechanically connected to contacts 13 and 14, respectively. The inductance and capacity are tuned to a frequency lower than, or substantially equal to, the lowest frequency to be repeated. In a typical case where frequencies covering a range of from 6,000 to 30,000 cycles are to be repeated, the inductance has a value of approximately 150 mil henries, the capacity is of such value as to resonate with the inductance at about 6,000 cycles, the resistances 22 and 23 each have a maximum value of about 15,000 ohms, and the resistance 11 and 12 each have a maximum value of about 48,000 ohms.

When the contacts 24 and 25 are set to cut all or nearly all of the resistance 22, 23 out of circuit, the impedance of the part of the equalizing shunt that is included between the contacts 24 and 25 is of course, very low for the frequency of 6,000 cycles to which the inductance and the capacity are tuned, and increases with frequency so that the impedance of this part of the shunt is materially higher for 30,000 cycles than for 6,000 cycles. In other words, a curve plotted between impedance of this part of the shunt as ordinates and frequency as abscissae, sloped downward, or gradually falls, from the 30,000 cycles point to the 6,000 cycle point. If the setting of contacts 24 and 25 be changed to include all or a large portion of the resistances 22 and 23 in circuit, the impedance frequency curve for the part of the equalizing shunt that is then included in the circuit will fall more gradually from the 30,000 cycle point to the 6,000 cycle point, for the impedance at 6,000 cycles will be increased

by practically the amount of the resistances 22 and 23 that has been included in circuit, whereas the impedance at 30,000 cycles will not be materially changed inasmuch as the reactive component of the impedance at 70 this frequency is high compared to the impedance of the resistance 22 and 23 and is practically at right angles to the resistance component of the impedance. Thus, as the contacts 24 and 25 are moved toward each other, the effect of the equalizing shunt is to tend to reduce the repeater gain more for the lower frequencies of the frequency range between 6,000 and 30,000 cycles than for the higher frequencies of this range. Therefore, when line attenuation decreases and the contacts 13 and 14 of the potentiometer 10 are moved toward each other to reduce the repeater gain sufficiently to approximately counteract the decrease of line attenuation for 30,000 cycles, that is, sufficiently to maintain the difference between the transmission level at the transmitting end and that at the receiving end of the line section the transmission loss of which the repeater is intended to control, approximately constant for 30,000 cycle current, the simultaneous movement of the contacts 24 and 25 toward each other causes the equalizing shunt to tend to increase the repeater gain for 6,000 cycle current without tending to materially increase it for 30,000 cycle current; and the difference between the amount of repeater gain that a given change in adjustment of the shunt by the change of setting of contacts 24 and 25 tends to effect for low frequencies and the amount that it tends to effect for high frequencies should, of course, be made approximately equal to the arithmetical difference between the decrease of line attenuation for the high frequencies and the decreases of line attenuation for the low frequencies. A battery 26 maintains grids 27 and 28 of the second stage of the repeater at potentials such that these grids draw substantially no current. It is, of course, to be understood that the expression low frequencies here refers to the lower frequencies of the frequency range transmitted, and not to the frequencies below the resonance frequency of the equalizing shunt. It is also to be understood, of course, that in stating that the changes of distortion produced by the potentiometer and equalizing shunt should be equal and opposite to those due to the line attenuation, the line referred to is the section of line the transmission loss of which the repeater is intended to control. In Fig. 2 also, a two stage, push-pull electron discharge repeater is shown for repeating from a line section 3, which extends west to a line section 5 which extends east. The first stage of the repeater feeds the second stage through a gain adjusting po-

tentiometer 30, which has inherent transmission equalizing properties, as will be explained below. The potentiometer consists of a resistor element composed of sections 31, 32, and 33, a resistor composed of sections 34, 35, and 36, tap connections 37, 38, 39, 40, 41, 42, 43, and 44 leading from the ends of the resistor sections, contacts 45 and 46 adjustable for connection to the free ends of the tap connections, and a loop circuit comprising capacity 47 and inductance 48 connected between the resistor sections 33 and 34. The loop circuit is tuned to a frequency higher than, or approximately equal to, the highest frequency that is to be repeated. The tap connection 40 comprises little or no resistance. The tap connections 37, 38, and 39 are resistance tap connections, the resistance comprised in tap connection 39 being great in comparison to the resistance of the resistor section 33, the resistance of tap connection 38 being larger than that of tap connection 39 and being great in comparison to that of resistor sections 32 and 33 in series, and the resistance of tap connection 37 being larger than that of tap connection 38 and being great in comparison to that of resistor sections 31, 32, and 33 in series. The part of the potentiometer shown below the tuned loop circuit is symmetrical with the part above the loop, and contacts 45 and 46 are preferably connected mechanically by means (not shown) whereby these contacts may be moved simultaneously toward or away from each other. A battery 26 maintains the grids 27 and 28 of the second stage of the repeater at potentials such that these grids draw substantially no current.

As the contact 45 is moved from a tap connection of one resistance value to the next tap connection of higher resistance the amount of resistance in series circuit between the contact 45 and the tuned loop increases by the sum of the resistance of the resistor section between the two tap connections plus the difference between the resistances of the two tap connections; and the potential of the grid 27 is affected as though the connection of the grid were simultaneously shifted from the right-hand end of the tap connection of lower resistance to the right-hand end of the other, or higher resistance tap connection. The operation of the part of the potentiometer that is shown below the tuned loop will, of course, be the same as the operation of the part shown above the loop.

Supposing that frequencies covering a range from 6,000 cycles to 30,000 cycles, for example, are to be repeated, and that the capacity 47 and inductance 48 are tuned to 30,000 cycles, then when the contacts 45 and 46 are set on low resistance tap connections 40 and 44, the voltage drop across the tuned

loop, and therefore the alternating voltage across the grids 27 and 28 (half of which latter voltage is applied to the circuit of one of the grids, the other half being applied to the other grid), is, of course, relatively high for the resonant frequency of 30,000 cycles, and decreases with frequency to a comparatively low value for a frequency of 6,000 cycles. In other words, a curve plotted between impedances across the loop as ordinates and frequencies as abscissae slopes downward, or gradually falls from the 30,000 cycle point to the 6,000 cycle point. When line attenuation decreases, contacts 45 and 46 are moved away from each other to increase the ratio of the impedance of the part of the potentiometer in circuit therebetween to the impedance of the part of the potentiometer, the voltage drop across which is the alternating voltage across grids 27 and 28. The effect of increasing the amount of the resistance of tap connections 37 to 44 that is included in circuit, is to tend to reduce the repeater gain sufficiently to more than counteract the decrease of line attenuation at all frequencies. However, the simultaneous effective shifting of the connections of the grids 27 and 28 to the potentiometer to include between the effective points of connection an increment of impedance that is relatively greater at 6,000 cycles than at 30,000 cycles, tends to increase the repeater gain for 6,000 cycle current more than for 30,000 cycle current. The difference between the gain decrease that the change of setting of the potentiometer produces for high frequencies and the gain decrease that it produces for currents of low frequencies in the frequency range to be transmitted, should be made approximately equal to the difference between the decrease of line attenuation for the high frequencies and that for the low frequencies.

Preferably, in determining the proper values for the resistances of section 31 to 36 and tap connections 37 to 44, these resistances are first calculated approximately, in the manner indicated below, and the actual values to be used are then ascertained by trial.

Fig. 3 is designed to facilitate explanation of the method of calculating the resistance values approximately. In this figure E_0 represents the voltage generated in the tubes of the first amplifier stage of Fig. 2, Z_1 represents the plate filament impedance of the tubes of the first stage, Z_0 represents the impedance presented across grids 27 and 28 and is assumed to be large in comparison with impedances Z_1 , Z_2 , Z_3 , Z_4 , Z_5 represents the impedance of the part of resistance sections 31 to 36 which lies between the two tap connections to which the potentiometer input leads are connected at any

given time, Z_2 represents the impedance of the tap connection on which the input leads terminate at that time, Z_3 represents the impedance of the tuned loop 47-48, and E_g represents the voltage across grids 27 and 28.

The current flowing through the input leads into the potentiometer is

$$10 \quad I = \frac{E_0}{Z_1 + Z_2 + Z_3 + Z_4}$$

and E_g will equal $I (Z_1 + Z_2)$, which equals

$$15 \quad E_g \left(\frac{Z_1 + Z_2}{Z_1 + Z_2 + Z_3 + Z_4} \right).$$

The attenuation produced by the potentiometer equalizer is

$$20 \quad \frac{E_g}{E_0} = \frac{Z_1 + Z_2}{Z_1 + Z_2 + Z_3 + Z_4},$$

and this ratio may be converted to loss in 800 cycles miles of standard 19 gauge cable by multiplying the log of the reciprocal of 25 the ratio by 21.13, in accordance with the commonly used formula, miles loss = 21.13 log (E_0/E_g) .

Let it be assumed that the known value of Z_4 is 12,000 ohms, and that the total gain 30 produced in the amplifying elements of the repeater is 30 miles, (regardless of frequency), and that the line loss under the most unfavorable weather conditions can be taken to be 18 miles more for 30 kilo-cycle 35 current than for 6 kilo-cycle current. Then it will be necessary for the potentiometer-equalizer (when at its highest gain setting) to produce for the 6 kilo-cycle current a loss 18 miles greater than the loss produced 40 for 30 kilo-cycle current; or in other words, the potentiometer-equalizer loss for 6 kilo-cycle current must be somewhat in excess of 18 miles, since even its minimum loss for 30 kilo-cycle current will, of course, be appreciable. The impedance Z_3 should be made high enough for 30 kilo-cycle current, to prevent this minimum loss from being excessive, but must be made low enough for 6 kilo-cycle current to have the potentiometer- 45 equalizer loss for the 6-kilo-cycle current in excess of 18 miles when the potentiometer-equalizer is at its lowest gain setting. Assume a value of say 50,000 ohms for Z_3 at 30 kilo-cycles. Then for this frequency the 50 potentiometer-equalizer loss with the potentiometer-equalizer at its highest gain setting will be

$$60 \quad 21.13 \log \frac{0 + 0 + 50000 + 12000}{0 + 50000} = 2 \text{ miles.}$$

Then, since the potentiometer-equalizer at its highest gain setting is to produce a loss for 6 kilo-cycle current 18 miles greater than its loss for 30 kilo-cycle current, its loss for 5 6 kilo-cycle current must be 18+2 miles, or

20 miles, at this setting. Having determined this loss, the value of Z_3 for 6 kilo-cycle current can be obtained as follows:

$$70 \quad 20 = 21.13 \log \frac{E_0}{E_g};$$

whence

$$75 \quad \frac{E_0}{E_g} = 9 \frac{0 + 0 + Z_3 + 12000}{0 + Z_3};$$

whence $Z_3 + 1500$ ohms.

We may now proceed to calculate the values that Z_1 and Z_2 should have for some other setting of the potentiometer, say for the lowest gain setting—that is, the setting 80 in which contacts 45 and 46 are on tap connections 40 and 44, respectively. Let it be assumed that the maximum gain change to be produced for 30 kilo-cycle current by changing the setting of the potentiometer- 85 equalizer is 13.5 miles, or, in other words, that the minimum gain of the repeater for 30 kilo-cycle current is to be $(30-2)-13.5=28-13.5=14.5$ miles, or, in other words, that the maximum loss to be produced by the 90 potentiometer-equalizer for 30 kilo-cycle current is to be 15.5 miles, or, in other words, that for the lowest repeater gain setting of the potentiometer-equalizer the loss produced by that device for 30 kilo-cycle current 95 is to be 15.5 miles = 21.13 log

$$Z_1 + 50,000 \over Z_1 + Z_2 + 50,000 + 12,000; \quad (1)$$

and let it be further assumed that the line 100 characteristics are such that the maximum gain change to be produced for 6 kilo-cycle current by changing the setting of the potentiometer-equalizer is 5 miles, or, in other words, that the minimum gain of the repeater for 6 kilo-cycle current is to be $(30-20)-5=10-5=5$ miles, or, in other words, that the maximum loss to be produced by the potentiometer-equalizer for 6 kilo-cycle current is to be 25 miles, or, in other words, that for the lowest repeater gain setting of the potentiometer-equalizer the loss produced by that device is 25 miles 105

$$= 21.13 \log \frac{E_0}{E_g} = 21.13 \log \quad 115$$

$$\left(\frac{Z_1 + 1,500}{Z_1 + Z_2 + 1,500 + 12,000} \right) \quad (2)$$

We may now substitute numerical trial values for Z_1 and Z_2 in equations (1) and 120 (2) to ascertain the proper values of Z_1 and Z_2 . It will be found that $Z_2=300,000$ ohms and $Z_1=20,000$ ohms will be satisfactory values for these impedances. Thus, if in Fig. 2 the impedance of the loop circuit is 1,500 ohms for 6 kilo-cycle current, and the sum of the impedances 31, 32, 33, 34, 35, and 36 is 20,000 ohms, and the sum of impedances 37 and 41 is 300,000 ohms, then, for the repeater assumed, the repeater gain with the 125 130

contacts 45 and 46 on tap connections 40 and 41, respectively will be 10 miles for 6 kilo-cycle current and 28 miles for 30 kilo-cycle current; and when the contacts 45 and 46 are moved to tap connections 37 and 41 the gain will be reduced to 5 miles for 6 kilo-cycle current and to 14.5 miles for 30 kilo-cycle current. Thus, the change of setting will reduce the gain for 30 kilo-cycle current 10 by 13.5 miles and will reduce the gain for 6 kilo-cycle current by only 5 miles.

The proper values of resistances 38, 39, 42, 43, 31, 32, 33, 34, 35, and 36, in Fig. 2, necessary to give the repeater gains requisite 15 to compensate for changes of line attenuation varying with frequency may be determined in the fashion in which the impedances Z_1 and Z_2 have been determined above, numerical trial values being substituted in equations (1) and (2) until such values have been obtained for all of the potentiometer-equalizer resistances as will give, for the various settings of the potentiometer equalizer and for the various frequencies to be transmitted, repeater gains approximately the theoretically correct ones as closely as practicable.

In the above calculations the impedances Z_1 , Z_2 , Z_3 , and Z_4 , have been used without 30 regard to the vector relation of their components, because only approximate results were desired, and experience has shown that sufficient accuracy is obtained with this method.

While balanced potentiometers have been disclosed, appropriate for the balanced amplifiers shown, it is clear that the invention is also applicable to repeaters and potentiometers not of the balanced type. The specific values of frequencies mentioned herein to facilitate the explanation of the principle of the invention, are, of course, merely illustrative values, and the invention is not restricted to use in connection with frequencies 45 of such values.

The invention claimed is:

1. An attenuating device and an input and an output lead therefor, said device comprising a resonant circuit, a resistance, means 50 for connecting an adjustable amount of said resistance between said circuit and said input lead, and means for so connecting said output lead to said resistance that during normal operation of said device said output lead is at a potential between the potentials of the points of connection of said input lead and said circuit to said resistance.

2. A repeater for connection in a transmission line, said repeater comprising an electron discharge tube having an anode, an electron discharge tube having a control elec-

trode, and a device adjustable to so change the repeater gain as to compensate for unequal variations in line attenuation at different frequencies, said device comprising a 65 resonant loop, a resistance, means connecting said resistance to said control electrode, and means movable relatively to said resistance for connecting an adjustable amount of said resistance in series between said anode and 70 said loop, and for thereby causing said control electrode to be connected to said resistance at a point which during repeating is at a potential between the potentials of the points of connection of said anode and said 75 loop to said resistance.

3. A potentiometer and an output lead therefor, said potentiometer comprising a resistance element, a tuned loop circuit connected to one end thereof, tap connections 80 of different resistances leading from points on said element, and a contact adjustable to engage the free ends of said tap connections, and said output lead being connected to a point on said potentiometer electrically remote from said tuned loop circuit.

4. A wave transmission system comprising a potentiometer and a source for supplying thereto currents of a relatively low frequency and a relatively high frequency, said potentiometer comprising a resistance element, an output lead connected to one end of said element, a loop circuit connected to the other end of said element and tuned to a frequency substantially as high as said relatively high 95 frequency, tap connections of different resistances leading from different points on said element, and a contact adjustable to engage the free ends of said connections, the resistances of and between said tap connections, the resistance, inductance, and capacity of said tuned loop circuit and the impedance of said source being so proportioned that movement of said adjustable contact from a tap connection of one resistance to a tap 100 connection of a higher resistance causes a greater decrease in transmission at said relatively high frequency than at said relatively low frequency.

5. In a transmission line, a combined potentiometer and attenuation equalizer comprising fixed reactive impedance and variable resistance in shunt to the line and variable resistance and substantially no reactance in series with the line, and means for simultaneously so varying said shunt and series resistances as to compensate for unequal variations in line attenuation at different frequencies.

In witness whereof, I hereunto subscribe 120 my name this 16th day of June, A. D., 1922.
JACOB S. JAMMER.
